UNITED STATES PATENT OFFICE

ROBERT B. SCHINDLER, OF SPRING CITY, PENNSYLVANIA, ASSIGNOR OF ONE-HALF TO SCHUYLKILL VALLEY MILLS, INC., OF SPRING CITY, PENNSYLVANIA, AND ONE-HALF TO HOWARD HOSIERY COMPANY, OF PHILADELPHIA, PENNSYLVANIA

DESIGN FOR A STOCKING

Application filed November 28, 1931. Serial No. 41,903. Term of patent 14 years.

To all whom it may concern:

Be it known that I, ROBERT B. SCHINDLER, a citizen of the United States, residing at Spring City, county of Chester, and State of Pennsylvania, have invented a new, original, and ornamental Design for Stockings, of which the following is a specification, reference being had to the accompanying drawings, forming part thereof.

I claim:

The ornamental design for a stocking as

ROBERT B. SCHINDLER.
